DESIGN FOR A LACE COLLAR OR SIMILAR ARTICLE

Walter F. Breuss, Leonia, N. J.

Application July 17, 1940, Serial No. 93,741

Term of patent 3½ years

To all whom it may concern:

Be it known that I, Walter F. Breuss, a citizen of the United States, residing in Leonia, county of Bergen and State of New Jersey, have invented a new, original, and ornamental Design for a Lace Collar or Similar Article, of which the following is a specification, reference being had to the accompanying drawing, forming part thereof.

The figure of the drawing is a plan view of a lace collar or similar article showing my new design.

The design which is an open work is shown on a black background to bring out the details of the design.

I claim:

The ornamental design for a lace collar or similar article, as shown and described.

WALTER F. BREUSS.
